UNITED STATES PATENT OFFICE

PATRICK J. FITZGERALD, OF TORRINGTON, CONNECTICUT, ASSIGNOR TO THE FITZGERALD MANUFACTURING COMPANY, OF TORRINGTON, CONNECTICUT, A CORPORATION OF CONNECTICUT

DESIGN FOR A FOOD MIXING, JUICE EXTRACTING AND GRINDING APPARATUS

Application filed April 16, 1932. Serial No. 43,517. Term of patent 7 years.

To all whom it may concern:

Be it known that I, PATRICK J. FITZGERALD, a citizen of the United States, residing at Torrington, county of Litchfield and State of Connecticut, have invented a new, original, and ornamental Design for a Food Mixing, Juice Extracting and Grinding Apparatus, of which the following is the specification, reference being had to the accompanying drawings, forming part thereof.

In the drawings:

Fig. 1 is a perspective view showing the motor casing and handle of the device in one position.

Fig. 2 is a perspective view showing the same in reverse position, and

Fig. 3 is a perspective view showing the same in intermediate position.

In the respective positions shown the various utility devices may be applied for example, in Fig. 1 mixing beaters may be used; in Fig. 2 a juice extracting mechanism may be used, and in Fig. 3 a grinding mechanism may be used.

I claim:

The ornamental design for a food mixing, juice extracting and grinding apparatus, as shown and described.

In testimony whereof, I affix my signature.

PATRICK J. FITZGERALD.
